UNITED STATES PATENT OFFICE.

WILLIAM FREDERIC CANAVAN, OF MONTREAL, QUEBEC, CANADA.

SAFETY CLOSURE FOR WALL OPENINGS.

Application filed April 11, 1923. Serial No. 631,289.

To all whom it may concern:

Be it known that I, WILLIAM FREDERIC CANAVAN, a subject of the King of Great Britain, and residing at 264 Clifton Avenue, in the city of Montreal, in the Province of Quebec, in the Dominion of Canada, have invented a new and useful Improvement in Safety Closures for Wall Openings, of which the following is the specification.

10 The invention relates to a safety closure for wall openings as described in the present specification and shown in the accompanying drawings that form part of the same.

The invention consists essentially of the novel features pointed out broadly and specifically in the claims for novelty following a description containing an explanation in detail of an acceptable form of the invention.

20 The objects of the invention are to afford great facility in the opening and closing of windows and panels in grain elevators, mills, factories and other buildings where it is desirable to close the windows or wall panels in groups and to permit the ready opening of windows in the event of explosions or other unforeseen happenings and where it is an advantage for the openings to remain free of the closures following the 25 forceful opening due to such causes as occur through spontaneous combustion in grain elevators; to eliminate many of the inconveniences and undesirable features of sash operating devices; to furnish a simple 30 and inexpensive arrangement of parts containing well known mechanical contrivances applied in a novel manner and in new combination to produce efficiency in operation and safety in buildings, and generally to 35 provide a durable and serviceable device, economical in regard to maintenance and efficient in respect to safety.

In the drawings, Figure 1 is a vertical sectional view of a wall showing a group of 40 closures and the operating mechanism.

Figure 2 is a rear elevation of a portion of the wall of a building showing the closures and the operating device.

Figure 3 is a perspective detail of a ratchet.

Figure 4 is a perspective detail of a lever.

Figure 5 is a front elevation of an elevator wall showing a group of windows and

panels and the operating mechanism in dotted lines.

55 Figure 6 is a rear elevation of the same group of windows and panels.

Like numerals of reference indicate corresponding parts in the various figures.

Referring to the drawings, the windows 60 1 and panels 2 are preferably hinged at the upper ends to the frames 3, the hinges 4 being of any suitable make and allowing the windows and panels to hang downwardly so that their plates extend downwardly over 65 the next window or panel below of the group in the extensions 5.

The lugs 6 and 7 project outwardly from the sash of the window or frame of the panel preferably from a bar 8 though the latter 70 is not at all essential to the operation and to these lugs 6 and 7 the connecting rods 9 are pivotally secured at their outer ends and at their inner ends to the levers 10 and 11 in the fork 12, the pin stop 13 being secured 75 across said fork adjacent to the outer end to limit the extension of the connecting rods and levers.

The levers 10 and 11 are formed with a journal opening 14 at their upper ends and 80 are loosely mounted on the ratchets 15 and particularly on the extending hubs 16 of said ratchets, the latter being fixedly mounted on the transverse shafts 17 also carrying the fixedly mounted worm wheels 85 18.

The pawls 19 are held to the ratchets 15 by the springs 20 and are pivotally secured to the levers 10 and 11 and so long as the transverse shafts remain stationary the said 90 pawl and ratchet mechanisms hold the windows and pawls securely in either an open or closed position, but the transverse shafts 17 are rotatable in their bearings 21, therefore the windows or panels can always be 95 opened or closed though they will open by force therebehind independent of the rotation of the shaft and the pawls thereby move to a new position on the ratchets in which position they will remain on the closing of the windows and panels by the rotation of the said transverse shafts.

The vertical worm shafts 22 are journaled in the bearings 23 secured to the wall and carry the worms 24 coacting with the worm 100 wheels 18, thus locking the windows and

panels to their open positions through the said pawl and ratchet mechanisms until the worm shafts are turned by means of the hand wheel 25, when the ratchets will rotate and allow the windows and panels to close by their own weight.

Briefly the operation of the invention is as follows:—The windows and panels are first in their closed position and to open them the hand wheels of the worm shafts are turned, which rotates the worm wheels and consequently the transverse shafts. The ratchets turn with these shafts and being engaged by the pawls the levers are connected and operated to an extended position as far as desired.

The closing is accomplished by reversing the direction of the worm shaft and thus changing the positions of the ratchets and naturally bringing both pawls and ratchets to their first relative position, that is to say the pawls move down with the ratchets in rotation and keep to the same tooth. Meanwhile the windows or panels close by their own weight and are held there, unless an explosion should occur and cause them to fly open bringing the levers and connecting rods to their extreme extended positions and coincidentally drawing the pawls from tooth to tooth of each ratchet until the pin stops of the levers are reached when the pawls will hold to the ratchet teeth and as said ratchets are stationary because of the worm and wheel, the said windows and panels will be held to their open positions to be subsequently closed by the manual operation of the mechanism as explained.

It will be noticed that the closures and windows are pivoted through the lugs 26, which project inwardly, so that the natural tendency of the window or pawl is to swing under the pivots and thereby closely engage the wall therearound.

The worm shafts 22 extend through the frames 27 and the worms 23 are within said frames as the latter also form bearings for the transverse shafts.

What I claim is:—

1. In safety closures for wall openings, a hinged closure, pawl and ratchet mechanism for holding said closure to its open position and worm and wheel mechanism for opening and closing said closure independently of an emergency movement.

2. In safety closures for wall openings, a hinged closure, pawl and ratchet mechanism for holding said closure and for opening and closing operations, a worm and worm wheel mechanism and a lever operated through said pawl and ratchet mechanism by said worm wheel shaft.

3. In devices of the nature described, a closure hinged to close by its own weight, means for holding said closure to its open position, and means for rotating one mem-

ber of the aforesaid means while its coating member maintains the same position in relation thereto and follows the rotating member to permit the falling of the closure into place by gravity.

4. In devices of the nature described, a wall having an opening and frame therearound, a closure hinged from the upper portion, a transverse shaft journalled in bearings from said frame and a worm wheel carried thereby, a vertical shaft suitably journalled and having a worm engaging said worm wheel, a ratchet fixedly mounted on said transverse shaft and having an extension hub, a lever loosely mounted at the upper end on said extension hub, a connecting rod from said lever to said closure, and a pawl spring-held to said ratchet and pivotally secured on said lever.

5. In devices of the nature described, a wall having a plurality of openings and frame work there around, a plurality of closures hinged to close by gravity, a transverse shaft journalled in bearings from said frame and a worm wheel carried thereby, a vertical shaft suitably journalled and having a worm engaging said worm wheel, ratchets fixedly mounted on said transverse shaft and having extension hubs, levers loosely mounted at the upper end on said extension hubs, connecting rods from said levers to said closures, and pawls spring-held to said ratchets and pivotally secured on said levers.

6. In devices of the nature described, a wall having a plurality of openings and frame work there around, a plurality of closures hinged to close by gravity, a transverse shaft journalled in bearings from said frame and a worm wheel carried thereby, a vertical shaft suitably journalled and having a worm engaging said worm wheel, ratchets fixedly mounted on said transverse shaft and having extension hubs, levers loosely mounted at the upper end on said extension hubs, and having a forked end and a pin stop across said end, connecting rods from said levers to said closures, and pawls spring-held to said ratchets and pivotally secured on said levers.

7. In devices of the nature described, a wall having an opening and frame therearound, a closure in the form of a panel having hinges at the upper end secured to said frame and a connecting rod lug intermediate of its height, a transverse shaft journalled in bearings from said frame and a worm wheel carried thereby, a vertical shaft suitably journalled and having a worm engaging said worm wheel, ratchets fixedly mounted on said transverse shaft and having extension hubs, levers loosely mounted at the upper end on said extension hubs, connecting rods from said levers to said closures, and pawls spring-held to said ratchets and pivotally secured on said levers.

8. In devices of the nature described, a wall having an opening and frame there-around, a closure in the form of a window having its sash hinged at the upper end to 5 said frame and a bar across said sash for a connecting rod, a transverse shaft journalled in bearings from said frame, and a worm wheel carried thereby, a vertical shaft suit-ably journalled and having a worm engaging 10 said worm wheel, ratchets fixedly mounted on said transverse shaft and having exten-sion hubs, levers loosely mounted at the upper end on said extension hubs, connect-ing rods from said levers to said closures, 15 and pawls spring-held to said ratchets and pivotally secured on said levers.

9. In closures for wall openings, a group

of windows and panels in vertical and hori-zontal rows, a horizontal shaft for each hori-zontal row of windows or panels or both, 20 ratchets on said shafts for each closure and rotating therewith and having hubs extend-ing therefrom, levers mounted on said ratchet hubs and having stops at the ends, 25 pawls on said levers spring-held to said ratchets, connecting rods from said levers to said closures, a worm wheel on each of said shafts and a worm shaft having worms cor-responding to and coacting with said wheels 30 and operated by a hand wheel.

Signed at Montreal, Canada, this 28th day of March, 1923.

WILLIAM FREDERIC CANAVAN.
